DESIGN.

—o—
R. W. BINNS.

JUG OR VASE.

No. 20,063.

Patented July 29, 1890.

UNITED STATES PATENT OFFICE.

RICHARD WILLM. BINNS, OF WORCESTER, COUNTY OF WORCESTER,
ENGLAND.

DESIGN FOR A JUG OR VASE.

SPECIFICATION forming part of Design No. 20,063, dated July 29, 1890.

Application filed April 21, 1890. Serial No. 348,921. Term of patent 7 years.

To all whom it may concern:

Be it known that I, RICHARD WILLIAM BINNS, director of the Royal Porcelain Works, Worcester, and a subject of the Queen of Great Britain, residing at Worcester, in the county of Worcester, in the Kingdom of Great Britain, have invented and produced a new and original Design for a Jug or Vase, of which the following is a specification, reference being had to the accompanying photograph, forming a part thereof.

The leading features of the design are as follows: a conical fluted body with each flute terminating as a sort of separate blade with a pendant standing in relief on a short conical part, a bottom formed of a crenelated cone, a bead, and a second curved cone expanding to its junction with the cone forming the bottom of the body, a handle with ornamental device joining it to the lower part of the bottom, resembling the bottom of a Doric column at the base, and terminating as a sleeve round the body of the handle having a scroll attached thereto. The top of the handle is attached to the body by an ornamental device somewhat resembling the capital of a pillar or a crown. The body proper terminates with a crenelated pattern beading, and with a mouth resembling the sheath of an arum before its full expansion.

What I claim is—

1. The design for a jug or vase herein shown and described, the same comprising a crenelated base, a beading and expanded curved cone, a short contracting cone meeting this, a larger fluted cone above terminating on the cone below, each flute having a separate blade with pendants, a handle resembling a Doric column with the fluted lower part as a sleeve extending for only a short distance and having a scroll, the body terminating above as a crenelated beading and surmounted by a tall mouth resembling the sheath of an arum in shape.

2. In the design of a jug or vase herein described, the handle resembling a tapering pillar with fluted and beaded base and plain body bent over and joined at each end to a body fluted and beaded below and plain above the fluted portion.

In testimony whereof I have signed my name to this specification in the presence of two subscribing witnesses.

RICHD. WILLM. BINNS.
